(57) **ABSTRACT**

A fuel charge for use with a melting plate candle assembly includes an outer shell of fuel material surrounding an inner core of fuel material having different properties than the fuel material of the outer shell. The outer shell is substantially solid and may contain fuel additive that slows capillary flow of liquid fuel to the flame through the wick. The inner core may include liquid fuel, discrete solid fuel particles, or a solid fuel mass. The fuel additive is disposed in the fuel charge so as to slow migration of liquefied fuel to a flame on a wick only after a substantial portion of the fuel charge has been liquefied by heat from the flame.

BACKGROUND OF THE INVENTION

1. Field of the Invention

The present invention relates to fuel charges for candles, and more particularly to fuel charges having a plurality of distinct fuel constituents.

2. Description of the Background of the Invention

Candle fuel charges having a plurality of distinct constituents are often used to provide decorative and functional benefits. For example, some candles have a solid outer shell of a first wax surrounding a solid inner core of a second wax having a lower melting temperature than the first wax. The second wax includes a soft mixture of fragrance oil and a carrier, such as petrolatum or a low melting point wax. When a wick disposed in the inner core is burned, the first wax of the inner core is melted and burned, and the second wax of the outer shell contains the molten first wax therein. In one such candle, the solid outer shell may be refilled with replacement paraffin beads placed around a replacement wick after the original inner core wax is consumed.

Other multi-constituent candle fuel charges have gas bubbles, glass spheres, glitter, and/or other types of decorative materials entrained in a gel fuel material contained in a non-flammable container. Often the decorative materials are entrained into the gel fuel material while the gel fuel material is still molten immediately after being poured into a mold. The bubbles, glass spheres, and/or glitter are dispersed throughout and encapsulated by a substantially solid matrix of the gel fuel material after the gel fuel material cools below the melt temperature thereof. Different colorants and fragrances may be added to each layer of gel fuel material to create a multi-fragrance candle.

Yet other multi-constituent candle fuel charges have a glass vial containing fragrance oil partly embedded in a wax body parallel to and spaced from a wick. An open end of the glass vial extends upwardly from a top surface of the wax body through which the wick extends. Heat from a flame located at the wick warms the fragrance oil and disperses fragrance to the surrounding atmosphere without burning the fragrance oil.

In another multi-constituent candle, wax prill, i.e., wax pellets ranging in size between 500 microns and 2000 microns, embedded with scented volatile actives is com-

2

pressed in a compression mold into a multi-layered candle. At least one layer has a different color than an adjacent layer thereto. A smooth or textured outer surface finish may be created by applying a heat source to the compression mold while the candle is being compressed or by applying an over-dip coating.

SUMMARY OF THE INVENTION

10 In one aspect of the invention, a fuel charge for a melting plate candle assembly includes a solid outer shell of meltable first fuel material, the shell forming an inner peripheral wall defining an opening through a medial portion of the fuel charge, and an inner core encompassed within the outer shell, 15 the inner core comprising a second fuel material in a second form different than the outer shell.

In another aspect of the invention, a method of supplying liquefied fuel to a wick in a candle includes melting a portion 20 of a fuel charge into the liquefied fuel by direct convection from a flame on the wick and by conduction of heat from the flame to a heat transmissive surface supporting the fuel charge, collecting the liquefied fuel into a pool on the surface, delivering the liquefied fuel from the pool to the wick, and introducing a fuel additive that slows capillary flow of liquid 25 fuel through the wick into the pool after the pool has been formed.

In a further aspect of the invention, a fuel element for a melting plate candle assembly includes a core of meltable fuel material, a wick extending axially through the core and exposed at an end of the fuel element, and an outer shell of 30 meltable fuel material disposed around the core. The outer shell is disposed a distance from the wick sufficient to allow the outer shell to be melted when a flame is burning on the wick. An amount of fuel additive that slows capillary flow of 35 liquid fuel to the flame through the wick is entrained in the outer shell sufficient to thicken the meltable fuel material after being melted to slow flow of the melted fuel material along the wick to the flame, as compared to flow without the fuel additive, without preventing the melted fuel material from feeding the flame

40 Other aspects and advantages of the present invention will become apparent upon consideration of the following detailed description.

45 BRIEF DESCRIPTION OF THE DRAWINGS

FIG. 1 is an exploded isometric view of a melting plate candle assembly having a capillary pedestal, a wick holder with fins and incorporated wick, and a fuel element according to one embodiment of the present invention;

50 FIG. 2 is an isometric view of the melting plate, wick holder, and fuel element of FIG. 1 in an assembled, operational configuration;

55 FIG. 3A is a partial cross-sectional view of a melting plate assembly as seen along the lines 3-3 of FIG. 2, but with a fuel charge according to another embodiment of the present invention;

60 FIG. 3B is a partial cross-sectional view similar to that of FIG. 3 of a fuel charge according to yet another embodiment of the present invention;

65 FIG. 4 is a cross-sectional view of the fuel charge as seen along the lines 4-4 of FIG. 3;

FIG. 5 is an isometric view of a fuel element according to a further embodiment of the present invention for use with the melting plate candle assembly of FIG. 1; and

FIG. 6 is a cross-sectional view of the fuel element of FIG. 5 as seen along the lines 6-6.

DETAILED DESCRIPTION

Turning now to the drawings, a melting plate candle assembly **20** shown in FIG. 1 includes holder **22**, a concave melting plate **24** carried by the holder, a wick **26** carried by a wick holder **28**, and a fuel charge **30**. A capillary pedestal **32** is located approximately in the center of the melting plate **24**. The wick holder **28** includes a base portion **34**, a wick receiver **36**, such as a cylindrical tube, and a heat transmissive element, such as heat fins **38**. The base portion **34** of the wick holder **28** is shaped to fit closely over the capillary pedestal **32**, and may retainingly engage the capillary pedestal, such as magnetically, by snap-fit retention members, interlocking engagement members, or other suitable retention methods. The fuel charge **30** has an opening **40**, such as an elongate slot, through a medial portion thereof through which the heat fins **38**, wick receiver **36**, and wick **26** may pass, so as to place the wick in close proximity to a top surface of the fuel element. The fuel charge **30** is shown as a wax puck, and other shapes may be used in other embodiments within the scope of the present invention.

In FIG. 2, the melting plate candle assembly **20** is shown in an assembled operational configuration, showing the relationship of the elements in position for lighting or ignition of the wick **26** with a flame **42**. The wick holder **28** is positioned on the capillary pedestal **36** (not visible) with the heat fins **38** and wick **26** extending through the opening **40**. In one embodiment, the fuel charge **30** rests directly on the melting plate **24** in the operational configuration. Additional details of a similar capillary pedestal are discussed in U.S. patent application Ser. No. 10/780,028, filed Feb. 17, 2004, which is incorporated herein by reference in its entirety, and which discloses a melting plate candle having a solid fuel element, a melting plate, and a lobe which engages a wick holder for a wick, wherein the wick holder engages the lobe in such a manner as to create a capillary flow of melted fuel from the melting plate to the wick.

When using a solid fuel material, such as candle wax, in conjunction with a heat conductive wick holder **28**, solid fuel refill units similar to the fuel charge **30** may be shaped to fit a shape of the melting plate **24**, with a specific relationship to the wick holder **28**, which itself is engaged with the melting plate. For example, the melting plate **24** may be a decoratively shaped container, and wax may be provided in the form of fuel charge refill units specific for the container shape selected, such as round, square, oval, rectangular, triangular, or otherwise, so shaped that the wick holder assembly incorporated with the fuel element refill unit will fit and engage a complementarily shaped capillary pedestal **32**. The melting plate **24** and the wick holder **28** include heat transmissive materials, such as aluminum, to transfer heat from a flame **42** on the wick **26** by conduction to the fuel charge **30**, both directly through the wick holder and from the melting plate. Thereby, the fuel charge **30** is melted by heat from the flame **42** both by convection directly from the flame and by conduction through the wick holder **28** and the melting plate **24**.

The use of the melting plate assembly **20** in conjunction with heat conductive elements, such as the heat fins **38**, offers distinct advantages. It permits rapid formation of a pool of liquid fuel due to improved heat conduction into the fuel charge **30**. This in turn allows better regulation of the size and shape, as well as the temperature, volume, and depth of the pool of liquefied fuel to allow more efficient use of fuels present. For example, melting plates **24** of the present invention permit ease of refill, with little or no cleaning. In most instances, no cleaning is required, but if desired, the melting plate **24** may be conveniently washed in a manner such as

dish, plate, or bowl is washed, in a wash basin or in a dishwasher. The use of a capillary pedestal **32** on the melting plate **24**, in conjunction with heat fins **38** on the wick holder **28**, also reduces or eliminates retention of solidified excess fuel when the candle is allowed to burn itself out, and permits more complete and uniform burning of fuel charges that are other than round, e.g., square, oval, triangular, or in the shape of a flower or decorative object, etc. Further, the melting plate **24**, when used in conjunction with the capillary pedestal **32** and wick holder **28**, provides a device that may be self extinguishing, and improves or eliminates typical burning problems encountered with standard candles, such as tunneling, drowning, collapsing, cratering, and wick drift. Fuel elements utilizing the melting plates described herein are also more forgiving of formulation or process variances. Furthermore, the presence of a magnetic retention assembly to retain the wick holder **28** on the capillary pedestal **32** provides a margin of convenience.

In FIG. 3A, another embodiment of a fuel charge **50** for use with the melting plate assembly **20**, includes a solid outer shell **52** and an inner core **54** that is encompassed by the outer shell. The outer shell **52** is made of a substantially solid mass of a meltable fuel material, such as pressed candle wax. The inner core **54** is made of fuel material in a different form than the meltable fuel material of the outer shell **52**. In this embodiment, the inner core **54** is made substantially of closely packed discrete solid fuel particles **56**, such as wax beads, having a matrix of interstitial spaces **58** extending between the wax beads. The inner core **54** may also include, or alternatively be made substantially of, fuel materials in other different form, such as, gelled fuels, liquid fuels, low melting temperature solid fuels, wax prill, and mixtures thereof, for example. The outer shell **52** may be formed by compressing a charge of the wax beads **56** in a heated press, which melts wax beads around the periphery of the charge to form the outer shell **52** as a smooth, substantially solid exterior wall. The outer shell **52** includes an inner peripheral wall portion **60**, which defines an opening **62**, such as an elongate slot, through a medial portion of the fuel charge **50**, and a bottom cavity **64**. The opening **62** and bottom cavity **64** are sized to accept a wick **26** and wick holder **28** such that the wick, wick retainer **36**, and heat fins **38** extend through the opening, and the base portion **34** is disposed within the bottom cavity. As shown in broken lines, the base **34** of the wick holder **28** fits closely around a capillary pedestal **32** to form a capillary space **66** extending from near the melting plate **24** upwardly toward the wick **26** with the fuel charge **50** disposed at least partly on the melting plate. Liquid fuel, such as melted wax from the fuel charge **50**, is collected on the melting plate **24** to form a pool **68** around the capillary pedestal **32**. The liquid fuel travels upwardly from the pool **68** to the wick **26** through the capillary space **66** by capillary action.

A fuel additive **70** that slows capillary flow of liquid fuel to the flame through the wick and/or clogs interstitial spaces in the wick and/or breaks down wick fibers is contained within a portion of the fuel charge **50** in one embodiment of the invention. Some examples of the fuel additive **70** include a non-aqueous viscosity modifier, such as ethyl cellulose, stearamide, polyamide, hydroxypropylene cellulose, and mixtures thereof. The fuel additive **70** may also or alternatively include materials that slow capillary flow of liquid fuel to the flame, such as additives that clog interstitial spaces in the wick or that break down wick fibers. The fuel additive **70** in some embodiments may also include useful properties, such as being in the form of a dye, insect repellant, and/or fragrance. The fuel additive **70** is disposed in the fuel charge **50** such that the fuel additive is not immediately introduced

into the pool 68 of liquid fuel. In this manner a flame 42 is initially provided with as much liquid fuel as possible to cause the flame to burn vigorously and melt the fuel charge 50 as quickly as possible. After the fuel additive 70 is introduced into the pool 68, migration of liquid fuel up the wick 26 is slowed (as compared to migration of the liquid fuel without the fuel additive) an amount sufficient to continue feeding the flame 42, but which decreases the size and vigorousness of the flame after a substantial amount of the fuel charge 50 has been melted. Such action in some cases may reduce the heat transfer from the flame 42 and lowers the temperature of the pool 68 after the fuel charge 50 has been substantially melted. In one embodiment, the fuel additive 70 is disposed in an outer peripheral portion 72 of the outer shell 52, which may be one of the last areas of the fuel charge 50 to be melted. In another embodiment, the fuel additive 70 may also be retained in portions of the fuel particles 56 that are disposed in the fuel charge 50 to be some of the last particles to be melted. In another embodiment (not shown), the fuel charge 50 includes two or more discrete pieces, such as vertically stacked sections, radially concentric sections, and/or partial circumferential sections, which may be assembled around the wick 26 and wick holder 28. Each discrete piece may carry a different volatile active, such as a fragrance, such that each volatile active is dispersed into the surrounding environment at different times.

In operation, the fuel charge 50 may completely melt in a shorter period of time from the flame 42 on the wick 26 than a completely solid fuel charge, such as 30, due in part to the increased surface area of the fuel particles 56 in contact with melted wax from the pool 68. More rapid melting of the fuel element 50 may allow for more rapid release of volatile actives, such as fragrances or insect repellents, entrained within at least some portions of the fuel charge. Once the fuel charge 50 is completely or almost completely melted, lowering the temperature and consumption rate of the melted fuel in the pool 68 may allow for a more sustained, longer lasting release of the volatile actives into the surrounding environment, thereby providing the benefits of the volatile active for a longer time period.

In FIGS. 3B and 4, a further embodiment of a fuel charge 100 adapted for use with a melting plate candle assembly 20 includes an outer shell 102 surrounding an inner core 104. The outer shell 102 is in the form of a substantially solid wall of meltable fuel material, such as candle wax, and the inner core 104 is in the form of a liquid fuel material, such as flammable lamp oil, for example. The outer shell 102 defines an outer peripheral wall portion 106 spaced radially outwardly from an inner peripheral wall portion 108. The inner peripheral wall portion 108 defines an opening 110 through a medial portion of the fuel charge 100 extending from a bottom cavity 112. The opening 110 in one embodiment is an elongate slot adapted to receive the wick holder 28 and wick 26 therethrough in a manner as described previously herein. One or more volatile actives 114, such as fragrances and/or insect repellents, may be dispersed in one or both of the outer shell 102 and the inner core 104. In operation with a melting plate 24, wick 26, and wick holder 28, the fuel charge 100 rapidly forms a pool of liquid fuel on the melting plate once the outer shell 102 is melted to release the liquid fuel in the inner core 104, which may allow even more rapid release of the volatile actives 114 into the surrounding environment than the fuel element 50.

The outer shell 102 in one embodiment further defines an inner medial wall 116a spaced between the inner peripheral wall 108 and the outer peripheral wall 106. Another medial wall 116b extends between the inner peripheral wall 108 and

the outer peripheral wall 106. The medial walls 116a, 116b divide the inner core 104 into four compartments 118a, 118b, 118c, and 118d. In one embodiment, each compartment 118 is isolated from the adjacent compartments, and each compartment is filled with a liquid fuel carrying a different volatile active 114, so that different combinations of volatile actives may be emitted into the surrounding environment as the fuel charge 100 melts to form the pool. Although four compartments 118 are shown in FIG. 4, any number—from one to many—of compartments may be formed by providing fewer or additional medial walls 116, and different combinations of volatile actives, including having the same or no volatile active throughout all the compartments of the inner core, may be formed. In another embodiment, the fuel charge 100 may be divided into discrete sections in a similar manner as described previously herein. Each discrete section of the fuel charge 100 may carry a different volatile active 114, such as a fragrance, such that a user may assemble different combinations of volatile actives around the wick 26 and wick holder 28 to provide different selected effects and/or dispense different volatile actives into the surrounding environment at different times.

In one embodiment, a fuel additive 120 that slows capillary flow of liquid fuel to the flame through the wick, such as ethyl cellulose, is disposed in a portion of the fuel charge 100 in a manner to cause the flame to bum less vigorously after a substantial portion of the fuel charge has melted as described previously herein. The fuel additive 120 may be disposed in a peripheral portion of the outer shell 102, as shown in FIGS. 3B and 4, and/or may be disposed in liquid fuel contained in an outer compartment 118.

The fuel charge 100 may be formed in one embodiment by heat pressing candle wax into two opposing portions, such as an upper portion 122 and a lower portion 124, and heat welding the opposing portions together at a seam 126. In one method, the compartments 118 of the inner core may be filled with the liquid fuel prior to heat welding the opposing portions 122 and 126 together. In another method, the compartments 118 may be filled after the opposing portions 122 and 126 are heat welded together by injecting the liquid fuel through an injection hole into the compartments and subsequently plugging the injection hole.

In FIGS. 5 and 6, yet another embodiment of a fuel element 150 for use with a melting plate candle assembly 20 includes a wick 26 and a wick holder 28 disposed in a fuel charge 152. The wick 26 and heat fins 38 extend axially above a top end of the fuel charge 152, and a base portion 34 is disposed within a cavity 154 in a bottom end of the fuel charge. The fuel element 150 is adapted to be placed on a melting plate 24 with a capillary pedestal 32 disposed in the base portion 34 and the bottom end of the fuel charge 152 disposed on the melting plate 24 in a similar manner as described previously herein. The fuel charge 152 has an outer shell 156 of meltable fuel material, such as candle wax, surrounding an inner core 158 of meltable fuel material, which surrounds the wick 26 and the wick holder 28. Each of the outer shell 156 and the inner core 158 is a substantially solid mass at room temperature. The outer shell 156 is spaced a distance from the wick 26 sufficient to allow a flame 42 on the wick to melt the outer shell. Fuel additive 160 that slows capillary flow of liquid fuel to the flame through the wick, such as ethyl cellulose, is disposed in the outer shell 156 but not in the inner core 158. When initially lit, the flame 42 may be larger and rapidly melt the inner core 158 to form a pool of molten wax due to the free flow of melted wax to the flame through the wick 26. As the outer shell 156 is subsequently melted, the fuel additive 160 is introduced into the pool, which may slow the rate of migra-

tion of the molten wax up the wick 26 to the flame 42 and thereby decrease the size of the flame. An amount of the fuel additive 160 is disposed in the outer shell 156 that is sufficient to decrease the flame size and yet provide enough fuel flow through the wick 26 to continue feeding the flame 42.

In operation, the flame 42 melts the fuel charge 152 by direct convection and by conduction through heat transmissive surfaces such as the heat fins 38, base portion 34, and melting plate 24. The melted fuel collects into a pool of liquid fuel on the surface of the melting plate 24, and the liquefied fuel is delivered from the pool upwardly to the wick 26 by capillary action through a capillary space 162 formed between the base portion 34 and a capillary lobe 32 on the melting plate. The fuel material of the outer shell 156 introduces the fuel additive 160 into the pool after the pool has been formed, and in one embodiment, introduces an amount of the fuel additive into the pool that is sufficient to sufficient to slow migration of the liquefied fuel in the wick to the flame without extinguishing the flame only after a substantial portion of the fuel charge 152 has been melted.

The fuel charge 152 in one embodiment is substantially cylindrical, having the wick extending axially through a cylindrical inner core, which is surrounded by an adjacent outer shell. In other embodiments, the fuel charge 152 may have other shapes and may include intermediate layers and/or materials between the inner core and the outer shell and surrounding the outer shell. In yet another embodiment, the wick 26 is disposed in the fuel charge 152 without the wick holder 28 or carried by a wick holder that does not include the heat fins 38 and base portion 34, and no cavity 154 is disposed in the bottom end. In a further embodiment, the fuel charge 152 has only an axial opening through the inner core 158 adapted to accept a wick and/or wick holder therethrough. In an even further embodiment, the axial opening extends through the outer shell to allow a wick and/or wick holder to enter the axial opening from a side of the fuel charge 152.

INDUSTRIAL APPLICABILITY

The fuel charges of the present invention may be used to provide fuel to a flame on a wick portion of a melting plate candle assembly. Providing an inner core of fuel material different than a surrounding outer shell can allow the fuel charges to completely liquefy quickly, and thereby hasten emission of volatile actives that may be contained therein. Providing a fuel additive that slows capillary flow of liquid fuel to the flame through the wick in only a portion of the fuel charges can slow flow of the liquefied fuel to the flame after the fuel charge is substantially liquefied and thereby slow consumption of the liquefied fuel and increase the useful life of the fuel charge. Other useful benefits of the present invention will be apparent to those skilled in the art.

Numerous modifications to the present invention will be apparent to those skilled in the art in view of the foregoing description. Accordingly, this description is to be construed as illustrative only and is presented for the purpose of enabling those skilled in the art to make and use the invention and to teach the best mode of carrying out same. The exclusive rights to all modifications within the scope of the impending claims are reserved.

We claim:

1. A candle fuel element for a melting plate candle assembly, the fuel element comprising:
a fuel charge and a wick;
wherein the fuel charge further comprises an outer shell of meltable first fuel material, the outer shell forming an

inner peripheral wall defining an opening through a medial portion of the fuel charge, and an inner core encompassed within the outer shell, the inner core comprising a second fuel material in a second form different than the outer shell, wherein the second fuel material includes a plurality of discrete fuel particles comprising candle wax and a plurality of interstitial spaces dispersed between the fuel particles; and
wherein the wick is disposed in the opening and extends through the fuel charge.

2. The candle fuel element of claim 1, wherein the opening is an elongate slot.

3. The candle fuel element of claim 1 further comprising a volatile active carried by at least one of the outer shell and the inner core, wherein the first fuel material is candle wax.

4. The candle fuel element of claim 1 further comprising a first portion of the fuel charge including a first volatile active, and a second portion of the fuel charge including a second volatile active.

20 5. The candle fuel element of claim 1 further comprising a fuel additive that slows capillary flow of liquid fuel through a wick.

6. The candle fuel element of claim 5, wherein the fuel additive comprises a non-aqueous viscosity modifier disposed only in an outer peripheral portion of the outer shell.

25 7. The fuel charge of claim 1, wherein the outer shell extends entirely around the inner core.

8. The fuel charge of claim 1, wherein the fuel charge further includes a bottom cavity.

30 9. The candle fuel element of claim 1, wherein the fuel particles comprise wax prill.

10. A fuel charge adapted for use as a candle on a melting plate candle assembly, the fuel charge comprising:

an outer shell of candle wax, the outer shell forming an inner peripheral wall extending completely through the fuel charge; and

an inner core encompassed within the outer shell, the inner core comprising a second fuel material, wherein the second fuel material is made of substantially liquid fuel material at room temperature and wherein the liquid fuel material comprises a volatile active and inflammable oil.

11. The fuel charge of claim 10, wherein the second fuel material comprises gelled fuel.

45 12. A fuel charge for a melting plate candle assembly, the fuel charge comprising:

a first portion of the fuel charge including a first volatile active and a second portion of the fuel charge including a second volatile active;

a solid outer shell of candle wax, the outer shell forming an inner peripheral wall defining an opening extending completely through the fuel charge, whereby a wick may extend completely through the fuel element through the opening; and

an inner core encompassed within the outer shell, the inner core comprising a second fuel material in a second form different than the outer shell, wherein the second fuel material includes a plurality of discrete fuel particles composed of candle wax and a plurality of interstitial spaces dispersed between the fuel particles.

13. The fuel charge of claim 12, wherein the plurality of discrete fuel particles comprises wax prill.

14. The fuel charge of claim 12, wherein the plurality of discrete fuel particles comprises wax beads.

UNITED STATES PATENT AND TRADEMARK OFFICE
CERTIFICATE OF CORRECTION

PATENT NO. : 7,731,492 B2
APPLICATION NO. : 11/197839
DATED : June 8, 2010
INVENTOR(S) : Chris A. Kubicek
